MULTIGLAZING

Percy E. Knudsen, Pittsburgh, Pa., assignor to
Pittsburgh Plate Glass Company, Allegheny
County, Pa., a corporation of Pennsylvania

Application January 26, 1939, Serial No. 252,916

5 Claims. (Cl. 189—64)

The present invention relates to window construction involving a plurality of spaced sheets or panes of glass and it has particular relation to a construction in which one of the sheets or panes is removable to admit of cleaning or other manipulations of the glass.

One object of the invention is to provide a multiple glazed window construction which is simple and which admits of removal of one pane to give access to the interior of the construction without disturbing the second pane.

A second object of the invention is to provide a window construction in which there are no metallic parts having exposed surfaces both within and without the building in which the construction is employed.

In order to reduce heat transmission, it has been proposed to employ a plurality of spaced sheets of glass mounted in a frame in such manner as to provide an insulative dead air space or chamber. Transmission of heat through the windows is thus greatly reduced. However, in such construction difficulty has been encountered in the provision of an adequate seal about the edges of the glass to exclude moisture from the inner space. Such moisture tended during cold weather to condense and sometimes even left a permanent film upon the glass. It also tended superficially to attack the glass to produce a haze or bloom which could not conveniently be removed.

Another development of modern window constructions has involved the provision of metallic sashes, frames and other structural elements. Difficulty has been experienced with them because of high thermal conductivity. Considerable heat was transferred through them and at the same time objectionable moisture was precipitated upon them.

The present invention involves as one feature the provision of a window construction including inner and outer panes or plates of glass, the latter of which is clamped independently of the former, and the inner sheet is so secured as to admit of easy removal.

In such construction it is a simple matter to take out the removable inner glass and clean the affected surfaces without disturbing the outer glass, and thus affording access of the external air to the building.

As a further feature, the invention involves the provision of a window construction in which all parts that constitute good conductors of heat are interrupted within the construction, thus obviating cold surfaces that would constitute points

for moisture condensation within the building in which the construction is employed.

For a better understanding of the invention reference may now be had to the accompanying drawing in which—

Figure 1 is a fragmentary elevational view of a window constructed in accordance with the provisions of the invention.

Figure 2 is a fragmentary cross-sectional view taken substantially upon the line II—II of Figure 1.

In the drawing like numerals refer to like parts throughout.

As shown, a wall 10 defines an opening in which is disposed a window construction 11, having a ledge portion 12 and a shoulder 13, the latter of which is crowned about its edge with a layer 14 of cement constituting a seat for a metallic (iron) structural bar 16. The bar is preferably, approximately of T-like cross-sectional contour, and includes outer flanges 17, inner flanges 18, and a connecting web 19. The lower edge or flange 17 is spaced slightly from the shoulder 13 and the space is packed with a suitable caulking material 20, e. g. with asphalt or like bituminous material mixed with a filler such as whiting.

A wooden insulative bar 22 is disposed between flanges 17 and 18 with the upper surface thereof terminating below the upper edge of the former flange. The bar is, also, grooved to receive the upper portion of the second-mentioned flange and is secured in position by means of screws 24 extending through the flange 17 and terminating within the wood. The exposed lower portion of flange 18 is covered by an insulative layer 21 of plaster or other material.

Spaced sheets of glass 26 and 27 having an adhesive sealing tape or compound 28 about the edges thereof are disposed upon the bar 22, with the edges of the outer sheet (26) engaging the abutment provided by the inner face of the projecting edge of flange 17. A spacer bar 29 of wood or other suitable insulative material is disposed between the sheets or plates of glass and constitutes a clamp for plate 26. It is held in position by means of bolts 31, which include heads 32 disposed in suitable sockets in the lower face of bar 22 and stem portions 33 extending upwardly through openings 34 in bar 22. The opening 36 in spacer bar 29 is offset slightly inwardly with respect to the stem 33 and preferably is downwardly tapered. Head 37 of the bolt is downwardly tapered in such manner that as the nut is screwed into position, the bar 36 is

forced slightly outwardly in order firmly to grip the edge portions of the sheet or pane 26.

The inner sheet of glass is releasably maintained in position by means of a finish strip 38, approximately of inverted L-shaped cross-sectional outline and including a vertical branch 39, horizontal flange 41 and a downwardly-directed lip 42, the latter of which engages the margin of the glass 27. Member 28 is held in position upon the bar 22 and actuated toward the glass 27 by means of screws 43 which are threaded through the leg or branch 39 into suitable bushings 44 disposed in openings in bar 22. It will be manifest that the inner sheet of glass 27 may 15 be replaced by two or more spaced sheets or plates secured together by metallic marginal channels or like means to provide a unit that can be installed in the same manner as a single plate.

20 The mode of operation of the invention is practically self-evident from the foregoing description. It will be assumed that the metal bar 16 is disposed in position in the opening in the wall 10 and that the bar 22 is secured thereupon by 25 means of screws 24. Sheet or plate 26 is then pressed into position against the flange 17 and is secured from displacement by means of bar 29. Plate or sheet 27 is then slid into the opening with the margins thereof engaging the inner face 30 of said bar. Subsequently the finish strips 38 are mounted in position with the lip 42 engaging the glass and the screws 43 are driven home in order to exert firm pressure against the edges.

An important advantage of the construction 35 resides in the fact that frame elements 16 can be directly mounted in the window opening during or after the erection of the building walls. Subsequently the bars 22 can be disposed in position thereupon. Both sheet 26 and bar 29 can 40 then be mounted from the inferior of the building. This constitutes a substantial advantage where the sheets are large and at considerable height above the ground.

It will be observed that in the foregoing construction there are no metal parts extending from the exterior of the wall to the interior thereof. This is an advantage because metal parts 45 constitute excellent conductors of heat and therefore in cold weather the inner faces of metal parts when exposed become chilled and are subject to condensation of moisture. Such moisture of course causes rust of the parts, and it is unsightly and is otherwise objectionable. It will also be noted that the outer sheet or pane 26 is 50 clamped by bar 29 independently of pane 27 in such manner that the latter can be removed by simple release of finish strip 38 in order to admit of cleaning of the interior surfaces.

The form of invention herein shown and described constitutes a preferred form. However, 55 it is given primarily for purposes of illustration, and it will be apparent that numerous modifications may be made therein without departure from the spirit of the invention or the scope of the appended claims.

60 What I claim is:

1. A building construction embodying a wall having a window opening formed therein, metallic members providing a channel upon the marginal portions of the opening, said channel hav-

ing a wide outer flange and a narrow inner flange, both flanges being vertically disposed, the outer of the flanges projecting upwardly to provide an abutment for the margins of the outer sheet of glass, a bar of insulative material formed 5 to fill the space between the flanges and being provided with a portion fitting over the inner flange, an outer sheet of glass having marginal portions disposed upon the bar and abutting against the upwardly-projecting margin of the 10 outer flange, an inner sheet of glass disposed upon the bar, a spacing member disposed between the two sheets, a clamping plate of approximately inverted L-shape, cross-sectional outline 15 secured to the inner face of the bar by means of screws, the upper portion of the clamping plate engaging the inner face of the inner sheet of glass to clamp the latter in position.

2. A construction as defined in claim 1 in which the spacing bar is provided with means actuating 20 it outwardly toward the first-mentioned sheet of glass to clamp the latter in position independently of the inner sheet of glass.

3. A construction as defined in claim 1 in which the spacing bar is provided with means actuating 25 it outwardly toward the first-mentioned sheet of glass to clamp the latter in position independently of the inner sheet of glass, said means comprising screws disposed in openings formed in the spacing bar in eccentric relation with respect to the screw and a nut having a tapered 30 head screwed upon the bolt.

4. A window construction comprising an outer frame provided with a flange projecting inwardly, a sheet of glass engaging at its margin with 35 the flange, gripping means positively secured to the frame and maintaining the glass in position, a second sheet of glass secured in the frame in spaced relation to the first, to provide a dead air chamber, releasable clamping means secured 40 to the frame and engaging the latter sheet to maintain it in position, said gripping means for the first-mentioned sheet of glass including a bar secured to the frame and engaging along one edge of the glass, and means independent of the 45 second-mentioned glass to actuate the bar toward the first-mentioned glass, the latter means comprising a screw secured to the frame and extending through a conically tapered opening 50 formed in the bar, the screw being axially offset away from the first glass sheet with respect to the conically tapered opening and a nut having a downwardly tapered head upon the screw.

5. A window construction comprising an outer frame provided with a vertically disposed flange, a sheet of glass in the frame and engaging the flange and an approximately rectangular spacing bar directly secured to the frame, means for moving the bar upon the frame to press the glass into position against the frame, said means being operable to increase or reduce the pressure of the bar against the glass without releasing the latter, a second sheet of glass disposed in the frame and engaging the bar upon the side opposite to the first-mentioned glass and means secured to the frame and actuating the second-mentioned sheet of glass against said bar, both of said means being operable independently of each other.

PERCY E. KNUDSEN.
